UNITED STATES PATENT OFFICE.

MARK H. DAMERELL, OF WORCESTER, MASSACHUSETTS, ASSIGNOR TO WYMAN-GORDON COMPANY, OF WORCESTER, MASSACHUSETTS, A CORPORATION OF MASSACHUSETTS.

CRANK-SHAFT-TWISTING MACHINE.

Application filed March 10, 1926. Serial No. 93,741.

This invention relates to a machine for bending the cranks of a multithrow crank shaft after the forging operation. Many such crank shafts are forged with all of the 5 crank-pins and bearings disposed in a single plane, the different cranks being thereafter twisted on their crank pins or bearings to the desired angular relation.

Machines have been heretofore devised for 10 performing this bending or twisting operation, one such machine being shown in my prior Patent No. 1,274,390, issued August 6, 1918.

It is the general object of my invention to 15 provide an improved machine for such purposes, which is relatively simple and economical in construction, and which is rapid and efficient in operation.

A further object of my invention is to 20 build a machine which is quickly and easily adaptable to crank shafts of different sizes and designs, and in which the dies are of simple construction and easily manufactured.

My invention further relates to arrangements and combinations of parts which will 25 be hereinafter described, and more particularly pointed out in the appended claims.

A preferred form of the invention is shown in the drawings in which

30 Fig. 1 is a front elevation of my improved machine;

Fig. 2 is an end view, looking in the direction of the arrow 2 in Fig. 1;

35 Fig. 3 is a sectional end elevation, taken along the line 3—3 in Fig. 1;

Figs. 4 and 5 are views similar to Fig. 3 but showing the parts in different successive positions;

40 Fig. 6 is a partial sectional elevation, taken along the line 6—6 in Fig. 1;

Fig. 7 is a view similar to Fig. 6, but showing the crank shaft after the twisting operation;

45 Fig. 8 is an enlarged side elevation of one of the twisting dies, looking in the direction of the arrow 8 in Fig. 1;

Fig. 9 is a plan view of the parts shown in Fig. 8; and

50 Fig. 10 is an enlarged detail view of a latch construction to be described.

Referring to the drawings, I have shown my improved crank shaft twisting machine as comprising a heavy base 20 which may be

secured to a suitable foundation, and an actuating head 21 which may be moved and 55 guided vertically by a hydraulic press or by any other suitable actuating mechanism (not shown).

The crank shaft S to be twisted preferably has its end portions located in supporting 60 blocks 22 and 23 (Fig. 1) and is supported with the crank pins and bearings disposed in a vertical plane between holding dies 24 and 25 (Fig. 4).

Cam bars 26 are secured to the actuating 65 head 21 and are forced between rolls 27 and 28 as the head descends. Each roll 27 is fixed to the base 20 and each roll 28 is mounted on a sliding bracket 29, supporting one of the holding dies 24 or 25. Tension 70 springs 30 are provided for opening the dies as the cam bars 26 are withdrawn upwardly after the twisting operation.

Reference to Fig. 4 will show that the cam bars 26 are so shaped at their lower ends 75 that the holding dies will be forced strongly to the position indicated in Fig. 5 as soon as the actuating head begins its downward movement. The crank shaft S is thus firmly gripped and supported during the twisting 80 operation and is released for convenient removal and replacement as soon as the twisting operation is completed.

I also provide die blocks 31 and 32 (Figs. 6 and 7), which limit the twisting movement 85 of the crank pins and accurately determine the final position of the crank pins as they are twisted by the movable upper dies.

I will now describe the upper or twisting dies and their method of operation. Three 90 such dies are shown in the drawings, one for each of the end cranks of the shaft S, and a die for the two middle cranks of the shaft S.

A description of the right hand die 35, as viewed in Fig. 1, will apply equally to the other dies also. This die 35 (Fig. 8) comprises a roughly triangular block having recesses 36 engaging the main crank shaft bearings adjacent the crank to be twisted and at each side thereof. The die block is 100 also recessed as indicated at 37 to receive the cheeks at each side of the selected crank pin.

A U-shaped strap 38 is secured in a recess in the top of the die 35 and its depending 105 arms are provided with circular bosses 39 to

which are pivoted links 40 which are slotted at 41 (Fig. 2) to receive studs 42, fixed in the actuating head 21. Links 43 (Fig. 8) are pivoted in slots 44 (Fig. 9) in the die blocks 35, being secured therein by cross pins 45. The upper ends of the links 43 are freely slideable in guide blocks 46, also pivoted on the studs 42. Springs 47 are mounted on the links 43 between the lower headed 10 ends of the links and the guide blocks 46. Stop screws 48 are provided for the links 40, to limit their downward swinging movement.

Each die block 35 (Fig. 8) is provided with a stud 50 in its upper face, which stud 15 is grooved as indicated at 51, thus providing a head 52 for each stud. The heads 52 are projected through openings 53 (Fig. 9) in a lock plate 54, slideable longitudinally in a guideway 55 (Fig. 10) in the actuating head 20 21.

Each opening 53 is provided with a narrowed portion 56 (Fig. 9) adapted to receive the grooved portion of the stud 50 and to support the head 52 thereof above the plate 25 54. A tension spring 57 acts to draw the lock plate 54 yieldingly in locking position and a handle 58 (Fig. 1) is provided for moving the plate 54 in the opposite direction to release the studs 50.

30 A latch 59 (Fig. 10) is provided in the head 21, which engages a notch or shoulder 60 in the plate 54, when the latter is moved to releasing position. A spring 61 insures prompt downward movement of the latch to 35 holding position. A pin or stud 62 projects downward from the latch and is engaged by a projecting portion of the base 20 or of the parts supported thereon, as the actuating head 21 reaches extreme downward 40 position. Such engagement releases the locking plate 54, which will then be drawn to locking position by the spring 57. This movement of the plate 54 obviously will cause an engagement between the opening 45 53 and the grooved portion of the stud 50, as both the head 21 and dies are in their lowermost position.

The actuating head 21 is also provided with additional die blocks 64, 65, 66 and 67 50 (Fig. 1) which engage portions of the shaft S as the head reaches its lowest position and force all parts of the shaft to correct 55 position, particularly preventing the shaft from yielding or springing upward in the holding dies. The blocks 65 and 66 are provided with depending portions 65^a and 66^a as shown in dotted lines in Fig. 1 and adapted to extend between the parts of the cranks which are held by the lower dies and thus 60 aid in preventing displacement, either axially or vertically.

Operation.

I have described the details of construction of my improved crank shaft twisting

machine and I will now describe the operation thereof.

Assuming that the crank shaft has been placed in position between the holding dies 24 and 25 and rests upon the blocks 22 and 23, the handle 58 (Fig. 1) is then pulled outward, moving the lock plate 54 to releasing position. The several twisting die blocks 35 then fall downward by gravity, but are guided in their falling movement by 75 their links 40 and 43.

The position of the blocks before release is shown in Fig. 3 and the position at the end of the falling movement is shown in Fig. 4. It will be seen that the rigid link 40 raises 80 one end of each block 35, while the spring-pressed link 43 forces the other end of the block downward until the head 43^a of the link 43 engages the guide block 46, which is rocked about the stud 42 as the die block 85 moves downward.

Each die block is then positioned for engagement with the crank to be twisted thereby. The actuating head 21 is then moved downward, commonly by hydraulic mechanism (not shown), and the cam bars 26 thereupon act to yieldingly close the holding dies 24 and 25 onto the cranks which are not to be twisted. This movement takes place during the lost motion of the stud 42 95 90 and the links 40.

The links 40 thereafter act to rock the die blocks 35 to the right or the left, as the case may be, twisting the cranks angularly until they engage the fixed die blocks or stops 31. 100 (Fig. 7.) At the end of this twisting movement, the upper face of each die block has resumed its horizontal position and the headed studs 50 have passed through the openings in the lock plate 54, which has been 105 held in releasing position by the latch 59.

As the head 21 reaches its extreme downward limit of movement, the latch is pushed upward and the die blocks are all locked to the actuating head 21 which thereafter 110 moves upward, carrying the die blocks 35 to the original position indicated in Fig. 3.

At the extreme lower limit of travel, the die blocks 64, 65, 66, and 67 positively engage the crank shaft, bringing all parts 115 thereof to the desired final position. It will be understood that while the end die blocks are rocked in one direction, the middle block will be commonly rocked in the opposite direction, but by exactly similar mechanism. 120 It will also be understood that the entire twisting operation is usually performed immediately after the forging of the crank shaft, and while the metal is still very hot and very soft.

125 It will be seen that my improved machine is very readily adapted to different sizes and shapes of crank shafts, as the holding dies 24 and 25 and the die blocks 35 are all of simple construction and they may be readily 130

exchanged and replaced with comparatively small trouble or expense. The machine is herein shown as operating upon a seven bearing, six throw, crank shaft, for which

5 purpose it is particularly well adapted, but it will be understood that it may also be adapted for various other combinations of throws and bearings.

10 The machine is very rapid in operation and is particularly desirable from the fact that the dies 35 are raised clear of the bed by the return of the actuating head 21, so that there is ample clearance for inserting and removing crank shafts.

15 Having thus described my invention and the advantages thereof, I do not wish to be limited to the details herein disclosed otherwise than as set forth in the claims, but

What I do claim is:—

20 1. A crankshaft twisting machine having in combination, a holding die, a twisting die, actuating mechanism by which said twisting die is supported, means to release said twisting die from said actuating mechanism, 25 means to guide said twisting die to engage the work, and means to rock said twisting die as said actuating mechanism descends.

2. A crankshaft twisting machine having, in combination, a holding die and a twisting die, actuating mechanism by which said twisting die is supported, means to release said twisting die from said actuating mechanism, means to guide said twisting die to engage the work, and means to re-engage said 35 twisting die with said actuating mechanism before said actuating mechanism returns to raised position.

3. A crankshaft twisting machine having, in combination, a holding die and a twisting die, actuating mechanism by which said twisting die is supported, means to release said twisting die from said actuating mechanism, means to guide said twisting die to engage the work, and means to produce a rocking movement of said twisting die in contact with the work as said actuating mechanism descends and to thereafter raise said die with said actuating mechanism.

4. A crankshaft twisting machine having, 50 in combination, a holding die and a twisting die, actuating mechanism by which said twisting die is supported, means to release said twisting die from said actuating mechanism, means to guide said twisting die to engage the work, means to lock said holding die on the work as the actuating mechanism descends, and means to rock said twisting die in contact with the work also as said actuating mechanism descends.

60 5. A crankshaft twisting machine having, in combination, a lower holding die and an upper twisting die, an actuating member by which said twisting die is supported, means to cause said twisting die to descend and engage the work before movement of

said actuating member, and means to rock said twisting die in engagement with the work as said actuating member thereafter descends.

6. A crank shaft twisting machine comprising a lower holding die adapted to retain a crank shaft, an upper twisting die, an actuated head for said upper die by which said upper die is normally held in raised position, means by which said die may be manually released from said head thereby to be positioned on said crank shaft, means to actuate said head to operate said upper die, and automatic means to re-engage said die with the head after the twisting operation thereof. 70 75

7. A crank shaft twisting machine comprising a lower holding die adapted to retain a crank shaft, an upper twisting die, an actuated head for said upper die by which said upper die is normally held in raised position, means by which said die may be manually released from said head thereby to be positioned on said crank shaft, means to actuate said head to operate said upper die, and means to automatically re-attach said die to said head as the head approaches its lower limit of travel, whereby said die is returned to normal raised position as said head moves upward. 80 85 90 95

8. In a crankshaft twisting machine, an actuating head, a normally raised twisting die, means to guide said die to lowered work-engaging position before said head descends, and means to return said die to raised position as said head ascends. 100

9. In a crankshaft twisting machine, an actuating head, a normally raised twisting die, means to guide said die to lowered work-engaging position before said head descends, 105 said die being manually releasable for downward movement to work-engaging position before said head descends, means to give said die an operative twisting movement as said head descends, and means to return said die to normal raised position as said head ascends. 110

10. A crankshaft twisting machine comprising a lower die for holding a crank shaft and an upper die coacting therewith for twisting said shaft, an actuating head for operating said upper die, and automatic means to lock said holding die on the work as said actuating head begins its operative movement and before twisting movement of 115 120 said upper die.

11. A crankshaft twisting machine having, in combination, means to hold a flat forged crankshaft against rotation, with the cranks disposed substantially in a vertical 125 plane, an actuating head, and an upper twisting die connected by pivoted linkage to said head and receiving a twisting movement through said linkage as said head descends.

12. A crankshaft twisting machine hav- 130

ing, in combination, a holding die, a normally raised twisting die, means to release said twisting die from its raised position for movement by gravity to crank-engaging position, and means to thereafter move said die angularly to twist said crankshaft.

13. A crankshaft twisting machine having, in combination, a holding die, a normally raised twisting die, means to release said twisting die from its raised position for movement by gravity to crank-engaging position, and means to cause an angular idle movement of said twisting die in one direction during such movement by gravity and to thereafter cause a reverse angular twisting movement of said crankshaft.

14. A crankshaft twisting machine having, in combination, a separable holding die, a twisting die, adapted to partake of vertical and angular movements relative to said holding die and means to lock said holding die on the crankshaft between the vertical downward movement of the twisting die and the ensuing angular twisting movement thereof.

25 15. A crankshaft twisting machine having, in combination, a die for supporting a crank shaft against rotation, a normally raised die coacting therewith for twisting said shaft, and means to give said twisting die a guided downward movement and an angular twisting movement successively.

16. A crankshaft twisting machine having, in combination, a die for supporting a crank shaft against rotation, a normally raised die coacting therewith for twisting said shaft, means to give said twisting die a guided downward movement and an angular twisting movement successively, and means to thereafter restore said twisting die to raised position.

40 17. A crankshaft twisting machine having, in combination, dies for supporting a crank shaft against rotation, a plurality of normally raised dies coacting therewith for twisting said shaft, an actuating member, and means to guide said twisting dies to crank-engaging position, said actuating member being thereafter operated to give certain of said twisting dies an operative angular movement in one direction and certain other of said twisting dies an operative angular movement in a reverse direction.

55 18. A crankshaft twisting machine having, in combination, a twisting die, a vertically movable actuating member, and a retaining device by which said twisting die is normally held in raised position by said actuating member, said retaining device being manually releasable before the crank twisting movement of said twisting die by said actuating member.

60 19. A crankshaft twisting machine having, in combination, a twisting die, a vertically movable actuating member, and a retaining device by which said twisting die is

normally held in raised position by said actuating member, said retaining device being manually releasable before the crank twisting movement of said twisting die by said actuating member, and means to thereafter automatically restore said device to retaining relation with said die before the return movement of said actuating member.

70 20. A crankshaft twisting machine having, in combination, a holding die in which a flat forged crankshaft is supported with its cranks disposed substantially in a vertical plane, a normally raised twisting die, an actuating member, and operative connections between said actuating member and said twisting die, and means whereby the connections permit said twisting die to move downward while said actuating member remains in raised position and cause angular movement of said die during such downward movement.

75 21. The combination in a crankshaft twisting machine as set forth in claim 20, in which said actuating member causes a reverse angular twisting movement of said twisting die, subsequent to said first angular movement.

80 22. The combination in a crankshaft twisting machine as set forth in claim 20, in which said actuating member is effective through said connections to cause a reverse angular twisting movement of said twisting die as said member descends, subsequent to said first angular movement.

85 23. A crankshaft twisting machine having, in combination, means to hold a flat forged crankshaft with the cranks disposed substantially in a vertical plane, an actuating head, and an upper twisting die connected by a yielding compressible link and by a lost-motion positive link to said head, said twisting die receiving a twisting movement through said links as said head descends.

90 100 24. In a crankshaft twisting machine, an upper crank twisting die, an actuating head by which said die is normally supported, a connection by which pressure from said head may be positively applied to said die when unsupported thereby, a yielding connection from said head to a different point on said die, and means to release said die from said head.

105 25. In a crankshaft twisting machine, an upper crank twisting die, an actuating head by which said die is normally supported, a connection by which pressure from said head may be positively applied to said die when unsupported thereby, a yielding connection from said head to a different point on said die, and means to release said die from supporting connection with said head, while retaining both the positive and the yielding connections between said head and said die.

26. In a crankshaft twisting machine, an upper crank twisting die, an actuating head by which said die is normally supported, a connection by which pressure from said head 5 may be positively applied to said die when unsupported thereby, a yielding connection from said head to a different point on said die, and means to release said die from said head, said die being guided by said connections in falling movement to engage the work when thus released.
27. In a crankshaft twisting machine, an upper crank twisting die, an actuating head by which said die is normally supported, a 15 connection by which pressure from said head may be positively applied to said die when unsupported thereby, a yielding connection from said head to a different point on said die, and means to release said die from said head, said die being guided by said connections to engage the work when thus released in advance of operative movement of said actuating head.
28. A crankshaft twisting machine having, in combination, a holding die in which a 25 flat forged crankshaft is supported with its cranks disposed substantially in a vertical plane, a twisting die, an actuating member for said twisting die movable toward and from said holding die, and cam means operable by said actuating member effective to lock said holding die against said crankshaft during the operation of said twisting die.
29. A crankshaft twisting machine having, in combination, a holding die in which a 30 flat forged crankshaft is supported with its cranks disposed substantially in a vertical plane, a twisting die, an actuating member for said twisting die movable toward and from said holding die, and a cam bar on said actuating member effective to lock said holding die against said crankshaft during the operation of said twisting die.
30. A crank shaft twisting machine having in combination a die for clamping a crank shaft against rotation, a normally raised die adapted to move relative to said clamping die for twisting said shaft, and means to give said twisting die a guided 40 downward movement and an angular twisting movement successively.
31. A crank shaft twisting machine, having in combination, means to hold a flat forged crank shaft against rotation, with the cranks disposed substantially in a vertical plane, an actuating head, and an upper twisting die, linkage pivoted to said head and pivoted to said die, thereby to pivotally connect said head and die, means to 45 actuate said head, said linkage adapted to give a twisting movement to said die during actuation of said head.
32. A crank shaft twisting machine, comprising a lower die for supporting a crank shaft against rotation, an upper die adapted to 50 coact therewith in twisting said shaft, an actuating head, a support for said upper die pivoted on said head, and means to rock said die relative to said support during actuation of said head.
33. In testimony whereof I have hereunto affixed my signature.

MARK H. DAMERELL.
